UNITED STATES PATENT OFFICE.

WILHELMINA STANYO, OF CONGRESS PARK, ILLINOIS, ASSIGNOR TO BLUE BIRD FAVOR CO., INC., A CORPORATION OF ILLINOIS.

DESIGN FOR A LAMP SHADE.

Application filed November 30, 1928. Serial No. 29,062. Term of patent 7 years.

To all whom it may concern:

Be it known that I, WILHELMINA STANYO, a citizen of the United States, residing at Congress Park, in the county of Cook and State of Illinois, have invented a new, original, and ornamental Design for Lamp Shades, of which the following is a specification, reference being had to the accompanying drawing, forming part thereof.

The figure is a perspective view of a lamp shade showing my new design.

I claim:

The ornamental design for a lamp shade, as shown.

WILHELMINA STANYO.
